SIMON B. FLEISHER, OF PHILADELPHIA, PENNSYLVANIA.

Design No. 4,384, dated October 4, 1870.

DESIGN FOR A BOX FOR HOLDING AND DISPLAYING BRAIDS, TAPES, &c.

The Schedule referred to in these Letters Patent and making part of the same.

I, SIMON B. FLEISHER, of the city and county of Philadelphia and State of Pennsylvania, have invented and produced a new and original Design for "Alpaca Braid-Box," of which the following is a specification.

The nature of my design is fully represented in the accompanying drawing.

The design consists in forming a rectangular box, the interior of which is subdivided by means of partitions into twenty-five convenient spaces for holding braid.

The lid of the box, inside and outside, is lettered as follows:

"Twenty-Five Dozen," "The Star Alpaca Braids," "Every piece has our ticket inside." On the front

part of the box is lettered, "Alpaca Braids." Between the words alpaca and braids is inserted a star, each point of which has one of the following letters, F. S. B. & M. In the center of the star is placed a wreath, in which is inserted the words "Trademark."

Claim.

I claim as my invention—
The design for "Alpaca Braid-Box," as shown.
SIMON B. FLEISHER.
